(57) **CLAIM**

The ornamental design for a food roasting device, as shown and described.

DESCRIPTION

FIG. 1 is an isometric view of the food roasting device in an extended position showing my new design;

FIG. 2 is a top side view thereof;

FIG. 3 is a bottom side view thereof;

FIG. 4 is a right side view thereof;

FIG. 5 is a left side view thereof;

FIG. 6 is a front side view thereof;

FIG. 7 is a rear side view thereof;

FIG. 8 is an isometric view of the food roasting device in a retracted position;

FIG. 9 is a top side view thereof;

FIG. 10 is a bottom side view thereof;

FIG. 11 is a right side view thereof;

FIG. 12 is a left side view thereof;

FIG. 13 is a front side view thereof; and,

FIG. 14 is a rear side view thereof.
